UNITED STATES PATENT OFFICE.

FREDERICK CARDER, OF CORNING, NEW YORK.

DESIGN FOR A FLOWER HOLDER.

Application filed July 8, 1927. Serial No. 22,694. Term of patent 14 years.

To all whom it may concern:

Be it known that I, FREDERICK CARDER, a citizen of the United States, residing at Corning, in the county of Steuben and State of New York, have invented a new, original, and ornamental Design for a Flower Holder, of which the following is a specification, reference being had to the accompanying drawing, forming part thereof, in which:

Fig. 1 is a top plan view of a flower holder showing my new design; and
Fig. 2 is a side elevational view of the same.

I claim:
The ornamental design for a flower holder as shown.

FREDERICK CARDER.
